CURTAIN RAIL

Kiyotsune Miki, 73, 1-chome, Higashi-Kagaya-cho,
Sumiyoshi-ku, Osaka-shi, Japan

Filed Oct. 14, 1971, Ser. No. 189,484

Term of patent 14 years

Int. Cl. D8—09

U.S. Cl. D8—208

FIG. 1

FIG. 2

FIG. 3

FIG. 4

FIG. 5

FIG. 1 is a perspective view of a curtain rail showing my new design, the portions being shown broken-away to illustrate indeterminate length;

FIG. 2 is a side elevational view thereof;

FIG. 3 is a top plan view thereof;

FIG. 4 is a bottom plan view thereof;

FIG. 5 is an end elevational view thereof;

Right side view being identical with the left, is omitted.

Rear view being identical with the front, is omitted.

I claim:

The ornamental design for a curtain rail, as shown and described.
